US00D986251S

(12) **United States Design Patent** (10) **Patent No.:** **US D986,251 S**
Cheng (45) **Date of Patent:** **** May 16, 2023**

(54) **STAND COVER FOR ELECTRONIC DEVICE**

(71) Applicant: **Fintie LLC**, Columbus, OH (US)

(72) Inventor: **Nai Chu Cheng**, Columbus, OH (US)

(73) Assignee: **Fintie LLC**, Columbus, OH (US)

(**) Term: **15 Years**

(21) Appl. No.: **29/808,430**

(22) Filed: **Sep. 20, 2021**

(51) **LOC (14) Cl. 14-02**

(52) **U.S. Cl.**

USPC **D14/440**

(58) **Field of Classification Search**

USPC D14/440, 447, 250; 206/45.23, 320,
206/45.2; 361/679.55; 294/25; 224/218

CPC G06F 1/1628; G06F 1/1626; A47B 23/044

(57) **CLAIM**

The ornamental design for a stand cover for electronic device, as shown and described.

DESCRIPTION

FIG. 1 is a front perspective view of a stand cover for electronic device shown in a first open position, illustrating the device in use with a tablet computer and a stylus; FIG. 2 is a front elevation view of the FIG. 1 device in the first open position;

FIG. 3 is a rear elevation view of the FIG. 1 device in the first open position;

FIG. 4 is a right-side elevation view of the FIG. 1 device in the first open position;

FIG. 5 is a left-side elevation view of the FIG. 1 device in the first open position;

FIG. 6 is a top plan view of the FIG. 1 device in the first open position;

FIG. 7 is a bottom plan view of the FIG. 1 device in the first open position;

FIG. 8 is a rear perspective view of the FIG. 1 device in the first open position;

FIG. 9 is a front perspective view of the FIG. 1 device shown in a second open position, illustrating the device in use with a tablet computer and a stylus;

FIG. 10 is a right-side view of the FIG. 1 device in the second open position; and,

FIG. 11 is a front perspective view of the FIG. 1 device in a closed position.

The broken lines depict portions of the stand cover for electronic device that forms no part of the claim.

1 Claim, 11 Drawing Sheets
